UNITED STATES PATENT OFFICE

CHARLES J. ELDER, OF COLUMBUS, OHIO, ASSIGNOR TO COLUMBUS BED SPRINGS MANUFACTURING COMPANY, OF COLUMBUS, OHIO, A CORPORATION OF OHIO

CONVERTIBLE FURNITURE

Application filed November 30, 1928. Serial No. 322,675.

This invention relates to improvements in convertible furniture, in this particular reference to a combined bed and davenport structure, and has for the primary object the provision of a new and improved article of furniture which may be employed as a davenport or day-bed for ordinary use and when in what may be termed a folded or collapsed position, and wherein features of construction are presented which permit the device to be opened so as to assume an extended position making the same suitable for ordinary bed usage.

Another object of the invention resides in the combination article of furniture of the character set forth wherein the frame of the bed is of such form that with simple manual adjustments the device may be adjusted to assume either its folded or extended positions.

A further object of the invention resides in a simple and economical article of furniture possessing the convertible properties above described, wherein the device presents an attractive, finished appearance when set up for ordinary day use, and further, to provide a structure possessing both strength and lightness in weight as well as one which is economic to produce or manufacture.

With these and further objects in view which will appear as the description proceeds, the invention consists in the novel features of construction, combinations of elements and arrangements of parts hereinafter to be fully described and pointed out in the appended claim.

In the accompanying drawings:

Figure 1 is a view in front elevation of an article of furniture formed in accordance with the present invention.

Figure 2 is a top plan view thereof,

Figure 3 is an end elevation disclosing the device in its folded or collapsed position,

Figure 4 is a similar view showing the device in its open or extended position,

Figure 5 is a detail vertical sectional view on the plane indicated on the line 5-5 of Figure 3.

Referring more particularly to the invention the numeral 1 designates the improved convertible davenport and bed structure

comprising the present invention. In its preferred form the invention consists of a pair of ornamental end frames 2-2, which may be of any suitable design in conformity with furniture styles. In this instance the frames 2 are arranged in vertical longitudinally spaced order and have their lower portions provided with headed studs 3, which are receivable within key hole slots 4 formed in brackets 5, which are rigidly carried by an under frame structure 6. This under frame structure consists of end members 7-7, which carry the brackets 5, and said end members are united by longitudinally extending bars 8-8. The bars 8 constitute a support for the reception of a plurality of coil springs 9 to which a mattress, upholstering or any other suitable form of covering (not shown) may be applied in the customary manner.

Pivotedly mounted as at 10 upon the upper rear corners of the frame structure 6 is a folding back or frame structure 11. This back or frame structure comprises a substantially rectangular frame of metal bars which carry a spring base 12, the latter being also equipped with a plurality of coil springs 13, corresponding somewhat to the springs 9. It will be understood that there may be applied in any suitable manner to the springs 13, 80 mattress, upholstering or other suitable types or forms of covering, which may be either permanent or removable.

When the movable frame structure 11 occupies its open or extended position, as shown in Figure 4, it is supported horizontally and in registration with the upper part of the frame structure 6 by a plurality of folding legs 14, which latter are hinged at their upper ends to the frame structure 11, as indicated by the numeral 15. The legs 14 are connected with pivoted links 16 to the lower part of the frame structure 6, and the function of the links 16 is to cause the legs 14 to assume vertical positions when the frame structure 11 as a whole occupies a substantially horizontal plane. However, when the frame structure 11 is collapsed or elevated, as shown in Figure 3, the links 16 operate to fold or swing the legs 14 inwardly so that

the bed as a whole when collapsed will occupy but minimum space.

To retain the folding back or frame structure in its elevated position, I have provided the side bars of said frame with a pair of curved check links 17. These check links are pivoted as at 18 to the back frame structure 11, and intermediate of their length the links 17 are notched as at 19 so as to fit over the shank portions of rigid headed studs 20 which project from the end members 7. The outer or free ends of the links 17 are connected with coil springs 21 which have their opposite ends connected to the rear bars 8. The function of the springs 21 is to force the links 17 inwardly so that the engagement of the notches 19 with the studs 20 will be substantially automatic.

In order to provide for the convenient manual release of the links 17, so as to permit of the lowering of the back section 11, there is provided at each end of the bed a pair of bars 22. These bars have their lower ends pivoted as at 23 to the lower part of the end members 7. The bars 22, contiguous to their upper ends are connected by means of rods 24 with the spring press check links 17, so that the bars 22 are maintained in an upright position by the action of the springs 21. Connected with each of the bars 22 is a pair of depending rods 25, which have their lower ends connected with a longitudinally extending foot bar 26 suitably arranged within the confines of the frame structure 6. By pressing upon the bar 26 with the foot, sufficient pressure will be applied thereto so as to rock the bars 22. This results in lifting the check links 17 against the influence of their springs 21, so that the folding back section may be dropped to assume the extended or open position disclosed in Figure 4. It will be understood that I do not limit myself to a foot control for effecting this function but may employ any other manually operated trip either hand or foot operated.

In view of the foregoing it will be seen that the present invention provides a simple and improved article of furniture which during ordinary periods may function in the capacity of a day-bed or davenport, and when desired the device may be opened and extended so as to be useful and comfortable as an ordinary bed. The device is light in weight and easily operated, and due to its simple mechanical construction it may be manufactured and sold at a relatively low cost.

What is claimed is:

A convertible bed structure comprising a frame structure, a back section pivotally connected with said frame, a pair of links pivotally carried by said back structure, said links being provided with notches arranged to engage with fixed studs projecting from said main frame, springs connected with the

outer ends of said check links and serving normally to maintain the notches of the links in engagement with said studs, whereby they positively lock said back structure in a substantially elevated position relative to said main frame, a pair of inclined bars pivotally connected to said main frame, tie rods between said bars and said check links, and a manually operated member connected with said bars and extending longitudinally of the main frame for regulating swinging movement on the part of said check links.

In testimony whereof I affix my signature.

CHARLES J. ELDER.
